ATTORNEY

UNITED STATES PATENT OFFICE.

EDWARD F. DILLEY, OF HENNING, ILLINOIS.

CONCRETE POST.

1,296,053.

Specification of Letters Patent.

Patented Mar. 4, 1919.

Application filed June 3, 1918. Serial No. 237,994.

To all whom it may concern:

Be it known that I, EDWARD F. DILLEY, a citizen of the United States, residing at Henning, in the county of Vermilion and 5 State of Illinois, have invented certain new and useful Improvements in Concrete Posts, of which the following is a specification.

This invention relates to fence posts and particularly to a concrete fence post and has 10 for its primary object to provide such a post with a metal reinforcing core about which the body of the post is cast, the core being of metal formed with openings and lugs which latter and the core itself are 15 bent into such position and in such relation with the sides of the core as to thoroughly bind the latter with the concrete and form a strong and relatively indestructible article.

With these objects in view, together with 20 others which will appear as the description proceeds, the invention resides in the novel formation, combination and arrangement of parts, all as will be described more fully hereinafter, particularly pointed out in the 25 claims, and illustrated in the accompanying drawings, in which:

Figure 1 is a front elevation of the upper portion of the improved post.

Fig. 2 is a horizontal sectional view on 30 the line 2--2 of Fig. 1.

Fig. 3 is a perspective view of a portion of the core, before the concrete is cast around the same.

Fig. 4 is an elevation of a portion of the 35 blank from which the core is made, and

Fig. 5 is a perspective view of a wedge shaped pin for fastening wire fencing strands to the post.

In the drawings, 10 indicates the metal 40 core of the post which extends from end to end of the post and disposed substantially in the center thereof. The core 10 is made of a blank of sheet metal such as is shown in Fig. 4, the sides 11 and 12 of which are 45 bent perpendicularly to the body portion 13 to form a channel shaped member such as is shown in Figs. 2 and 3. In the side 11 of the core 10 are formed a number of openings 14 extending in a series running longitudinally of the side and may be of rectangular 50 form as shown, or any other shape desired.

From the opposite side 12 of the core 10 project a number of tongues 15 and 16, the 55 former being arranged in a longitudinal series near the edge of the side and the latter in a parallel series near the fold α be-

tween the body 13 and the side 12. The tongues 15 of one series are horizontally offset from the tongues 16 of the other series, as clearly illustrated in Fig. 3. The tongues 60 of both series are formed by cutting through the material of the blank on three sides of a rectangle so that the partly cut out portions may be bent outwardly at right angles to the side 12. The tongues in each series, further- 65 more, are arranged in pairs with their uncut edges adjoining so that when bent outwardly the tongues of each pair will lie parallel and slightly separated as shown in Fig. 3 to permit a wire strand being placed there- 70 between. Each tongue has a square or other shaped perforation 17 formed therein, the perforations of each pair being in vertical alinement and are designed to receive a tapering pin 18, see Fig. 5, which is driven 75 tightly therein for the purpose of holding the wire strand in position.

The body portion 13 of the core is also provided with tongues 19 formed in a manner similar to that of the tongues 15 and 16, 80 these tongues however are larger than the tongues 15 and are arranged in a single series of two longitudinal rows extending from end to end of the core. The tongues 19 are cut from the body 13 so as to leave a 85 side edge of each uncut, about which edge the tongue is bent laterally into position at a right angle to the body. The uncut edges of the tongues 19 alternate to permit said tongues, when bent to form two vertical 90 rows; they furthermore project in opposite directions, that is to say every other tongue of the series is bent outwardly about its edge nearest the fold β of the side 11 of the core, while the intermediate tongues are bent in- 95 wardly about their edges adjacent the fold. Each of the tongues 19 has formed there- 100 in two, preferably rectangular shaped open- ings 20.

In casting the post, the core 10 is set up in 100 the center of a mold of the desired size and form and the concrete poured therein in the usual manner, concrete flowing through the openings 14 in the side 11 of the core and also through the openings 21 left in the body 13 when the tongues 19 are bent into position. The openings 20 in the tongues 19 are 105 also filled by the concrete. The core will thus be secured in the center of the post by the concrete around the same and bound in 110 place by concrete filling said openings and through the connecting portions of metal

between said openings. The entire article is thus rendered exceptionally strong and practicably unbreakable. In placing the core within the mold, the side 12 is so disposed as to be outside the post, its inner surface or face lying in contact with one of the sides of the post so that the tongues 15 and 16 can project outwardly in position to receive the strands of fence wire.

10. The foregoing description and the drawings have reference to what may be considered the preferred, or approved form of my invention. It is to be understood that I may make such changes in construction, 15 and arrangement and combination of parts, materials, dimensions et cetera as may prove expedient and fall within the scope of the appended claims.

Having thus described my invention, what 20 I claim as new and desire to secure by Letters Patent, is:

1. A concrete post having a channel shaped metal core two sides of which are embedded in the post, the third side lying 25 against one face of the post, a plurality of tongues cut from one embedded side of the core and bent in opposite directions, each tongue having an opening formed therethrough, and openings in the other embedded side through which openings in the tongues and the openings in the side of the core from which the tongues were cut the concrete forming the post is adapted to flow.

2. A concrete post having a metal core 30 extending longitudinally thereof formed with a plurality of tongues cut therefrom and bent in opposite directions thereto and upon vertical axes, a plurality of smaller tongues also cut from the core and bent outwardly in pairs on horizontal axes, said latter tongues projecting without the post, and a plurality of openings in the core on the opposite side of the first named tongues through which openings and through the 35 openings left by bending the first named tongues, the concrete forming the post flows.

3. A concrete post having a channel

shaped core extending longitudinally thereof, one side of said channel lying exteriorly of the post and flatwise against the side 50 thereof, and two series of coöperating pairs of tongues each pair being cut from the exposed side of said core bent outwardly into close horizontal parallel relation slightly separated for supporting wire strands, the 55 pairs of tongues of one series being offset vertically and horizontally from those of the other series.

4. A concrete post having a channel shaped metal core extending longitudinally 60 thereof, one side of said core lying exteriorly of the post and against the side thereof, tongues cut from the body of the core and bent alternately in opposite directions and on opposite sides of said body and embedded 65 in the concrete, and other tongues cut from the side of the core without the post and bent outwardly in closely adjacent pairs with vertically alined perforations therethrough.

5. A core for a concrete post formed of a strip of plate metal bent into a channel shape and having a plurality of longitudinally arranged openings formed in one of the sides of said channel, two series of longitudinally arranged tongues cut from the other side of said channel, the tongues of each series being bent outwardly in pairs slightly separated with vertically alined perforations therethrough, the pairs of tongues 70 of said two series being offset from one another, and a single series of tongues cut from the body of the core and bent in opposite directions alternately on opposite sides of said body to form two rows of offset tongues, 75 each tongue having one or more openings therethrough.

In testimony whereof I affix my signature in presence of two witnesses.

EDWARD F. DILLEY.
